UNITED STATES PATENT OFFICE.

FRANZ WASCHEK, OF HAMTRAMCK, MICHIGAN.

REED-ORGAN.

1,307,715.

Specification of Letters Patent. Patented June 24, 1919.

Application filed May 10, 1918. Serial No. 233,630.

To all whom it may concern:

Be it known that I, FRANZ WASCHEK, a subject of the Emperor of Austria, resident of Hamtramck, county of Wayne, and State of Michigan, have invented certain new and useful Improvements in Reed-Organs, of which the following is a specification.

This invention relates to improvements in reed organs and the principal object of 10 the invention resides in the provision of a novel means for controlling the volume of the sound issuing therefrom.

Another object of the invention is to provide a novel means of operating the bellows 15 or pump in such a manner as to relieve the operator from much of the strain usually accompanying the playing of an organ.

With the above and other objects in view as will become more apparent as the description 20 proceeds, the invention consists in the novel combination, construction and arrangement of parts which will be set forth in the following specification, illustrated in the accompanying drawings and claimed.

25 Figure 1 is a front elevation of an organ constructed in accordance with this invention,

Fig. 2, is a vertical sectional view through the device taken on line 2—2 of Fig. 1,

30 Fig. 3, is a horizontal sectional view taken on line 3—3 of Fig. 1,

Fig. 4, is a vertical sectional view through the device taken on line 4—4 of Fig. 3,

Fig. 5, is an enlarged detail sectional view 35 through a portion of the device taken on line 5—5 of Fig. 3, and

Fig. 6, is an enlarged detail perspective view of one of the closures for the air passage.

40 Referring to the drawing by characters of reference the numeral 1, designates as an entirety the organ comprising a case 2, having a keyboard 3 in which the keys 4, are mounted. The case 2 has extending forwardly therefrom at its lower end and arranged centrally thereof a pair of arms 5 for supporting the bellows-operating pedals, which will be more fully hereinafter described.

50 Mounted on the forward ends of the arms 5 are bearings 6, in which is rotatably mounted a shaft 7, having attached to opposite ends the crank arms 8, on which are mounted the pedals 9, as clearly illustrated 55 in the drawing. Mounted on the shaft 9, between the arms 5, is a wheel 10, around

which a chain 11, runs and when the operator turns the shaft the chain will be driven. Extending longitudinally through the case 2, adjacent the bottom wall thereof is a shaft 12, which is mounted in suitable bearings 13 at opposite ends of the case and this shaft 12 is provided centrally with a sprocket 14, around which the chain 11, passes.

Mounted within the lower portion of the 65 case 2, is the bellows 19, which consists of a pair of heads 20, connected by a compressible body of flexible material 21. Formed near one end of the upper head of the bellows and adjacent the rear edge thereof is 70 an opening 22, which is closed by a valve 23, which valve opens to allow air within said bellows to escape while the same is being compressed. This valve opens into a reservoir 24, formed within the upper portion of 75 the case 2, and the front wall of said reservoir 24, is designated by the numeral 25, and pierced by apertures 26, which are adapted to be closed by the valves 27, mounted on the shafts 28. These shafts 28 pass through 80 a reservoir 29 formed in the case 2, just in front of the reservoir 24, and also through the front wall of the case. Knobs or pulls 30, are attached to the outer forward ends of the shafts 28, and serve as a controlling 85 means for the valves 27.

Extending longitudinally through the upper portion of the case 2 is an air passage 31 having three series of outlets or openings 32, which are arranged in staggered relation 90 and are adapted to be closed by the valves or closures illustrated in Fig. 6. One end of the passage 31 communicates with the chamber 29, so that air admitted to the said chamber 29, from the reservoir 24, will pass 95 into the passage 31, and escape when one of the openings 32, is uncovered. In order to produce sound upon the opening of any particular opening 32, the passage is formed with a number of offsets 33, upon which are 100 supported the reeds or tongues 34. It will thus be seen that when any one of the outlets 32 is opened the air in rushing past the reed or tongue mounted near that particular opening will cause the said reed or tongue 105 to vibrate and create a sound. It will be understood of course that the reeds or tongues and openings will be arranged to cooperate in producing musical sounds and the relative positions of the various outlets will 110 be made to meet varying requirements. For the present however the drawing illustrates

the conventional form of key-board and the valves controlled by the keys are arranged accordingly.

The keys 4, previously mentioned are piv-
5 otally mounted on a rod 35, which is ar-
ranged slightly in the rear of the keyboard
3, and extending upwardly from each indi-
vidual key is a stem 36, the upper end of
10 which is attached to the valve of the open-
ing for which the key was intended. Each
of these valves comprises a plate or base
block 37 having a facing material 38 formed
of a suitable soft substance which engages
15 the walls of its particular passage and forms
an air tight closure. For the upper series of
valves it will be necessary to offset the stems
36, as illustrated in Figs. 2 and 4, so as to
allow for the opening of the valves of the
20 lower series without interfering with the rest
of the valves.

In operation it will be seen that the organ-
ist drives the bellows to cause air under pres-
sure to enter the reservoir 24 and thus one
25 or more of the valves 27, may be opened
according to the volume desired. The user
then by playing of the various keys 4, will
uncover certain of the openings in the pas-
sage 31, and allow the air within the passage
31, to escape around the reeds or tongues 34,
30 causing the same to vibrate and produce
sound. Of course the volume of air passing
around the reed or tongues will vary accord-
ing to the amount of air admitted to the
35 passage and thus by the manipulation of the
pulls or knobs 30 the valves 27 may be con-

trolled and the volume of air increased or
decreased, so that soft or loud tones may be
produced at the will of the user.

While in the foregoing there has been
shown and described the preferred embodiment
of this invention it will be understood
that certain minor changes in the construction,
combination and arrangement of parts
may be resorted to without departing from
the spirit and scope of the invention as
claimed.

What is claimed is:—

In a reed organ of the character described,
the combination with a reservoir for contain-
ing fluid under pressure, a bellows and oper-
ating means therefor, of a chamber for re-
ceiving the fluid from said reservoir upon
the operation of said bellows, sound produc-
ing means, said chamber communicating
with said sound producing means, and valves
between said reservoir and said chamber for
controlling the amount of fluid admitted to
said chamber and thereby the volume of the
sound produced, other valves between said
chamber and reservoir and above said sound
producing means, one for each key of the
organ, each comprising an offset stem, a
plate, a facing material for the same, and
means for connecting the stems of said valves
with the keys of the organ, substantially as
described.

In testimony whereof I have affixed my
signature.

FRANZ WASCHEK.
